CLAIM

The ornamental design for an animal nursing apparatus, as shown and described.

DESCRIPTION

FIG. 1 is an isometric view of an animal nursing apparatus in accordance with the present application.

FIG. 2 is a front view of the animal nursing apparatus.

FIG. 3 is a back view of the animal nursing apparatus.

FIG. 4 is a side view of the animal nursing apparatus.

FIG. 5 is a top view of the animal nursing apparatus; and,

FIG. 6 is a bottom view of the animal nursing apparatus.

1 Claim, 6 Drawing Sheets
